GRIPPING MECHANISM

Filed Jan. 15. 1923

UNITED STATES PATENT OFFICE.

RICHARD LESTER WILCOX, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

GRIPPING MECHANISM.

Application filed January 15, 1923. Serial No. 612,838.

To all whom it may concern:

Be it known that I, RICHARD LESTER WILCOX, a citizen of the United States, residing at Waterbury, in the county of New Haven and State of Connecticut, have invented certain new and useful Improvements in Gripping Mechanisms, of which the following is a specification, reference being had therein to the accompanying drawings.

This invention relates to new and improved gripping mechanism more especially as applied to mechanism designed to have a rotary movement in a single direction.

It is the object of this invention, among other things, to provide a device that will permit the movement of a member in one direction, but will grip and hold the same against movement in the opposite direction, such mechanism being so arranged as to apply no friction to said member when moving, to so design the same that it will be relatively powerful in its action, but occupy the minimum space, may be shifted so that the said member may, if desired, be moved in both directions, and to provide simple and convenient means to keep the frictional surface clean and free from oil, chips or other foreign matter.

To these and other ends my invention consists in the gripping mechanism having certain details of construction and combinations of parts as will be hereinafter described and more particularly pointed out in the claims.

Referring to the drawings in which like numerals of reference designate like parts in the several figures;

Figure 1 is a fragmentary side elevation of a heading or upsetting machine with my improved gripping mechanism applied thereto;

Figure 2 is an enlarged end elevation of the gripping mechanism;

Figure 3 is a sectional elevation thereof, taken generally upon line 3—3 of Figure 2; and

Figure 4 is a sectional detail plan view of some of the parts, taken generally upon line 4—4 of Figure 3.

This gripping mechanism is particularly adapted for use with feed mechanisms now

well known and common in the art of heading and upsetting machinery, an example of such feed mechanisms being shown in Letters Patent No. 1,253,322 for feed mechanism, dated January 15, 1918, and also in Letters Patent No. 1,309,749 for feed mechanism, dated July 15, 1919.

My improved gripping mechanism is therefore shown as applied to the feed mechanism of a heading machine, merely for the purpose of illustration because it is equally as well adapted with any other type of mechanism.

Referring to the drawings, the numeral 10 designates the frame of a heading machine, 11 a rock lever journaled therein, 12 an arm fixed to said shaft having a block 13 that is adjustable therein by means of a rod 14.

The feed mechanism as shown herein consists in part of a roll frame 15 within which are rotatably mounted the roll shafts 16 and 17. An intermittent rotary movement is imparted to these shafts and the feed rolls (not shown) attached thereto through a gripping mechanism that is actuated by a carrier 18 rotatably mounted upon the roll shaft 16 and actuated from the arm 12 by the connection 19 operatively associated with the block 13.

Forming part of said gripping mechanism is a ring 20 which moves in a rotary path in the direction of the arrow in Figure 1 while the gripping mechanism is in engagement, but is stationary when the carrier 18 moves in the opposite direction to again engage the parts and continue the movement of the ring 20.

When the carrier 18 is moving about the axis of the shaft 16 clockwise, that is opposite to the direction of the arrow, no movement should be given the ring 20. To hold this ring against such movement is one of the objects of my invention.

Heretofore it has been customary to encircle the ring 20 by a strap containing leather or asbestos material as a friction wearing surface, the ends of which are adjustably joined by a bolt encircled by a spring, which passes through the free end;

of the strap. An example of this type of friction device is shown in the above patents. This friction is constant, when in fact friction is only required between the feed movement of the feed rolls and thus becomes a drag upon the power required to operate the heading machine.

With my improved mechanism I have overcome these and other objections to the present form of friction device by providing a device that is in action only when required, is a single unitary structure of relatively small size, comparatively light in weight, requires no power in its operation and can be so controlled as to allow, if necessary, the movable member to travel in opposite directions.

As shown, my mechanism consists essentially of a bracket 21, fixed to the frame 10 by bolts 22 and dowel pins 23, or the like, and having an opening 24 in one edge thereof, to the rear wall 25 of which is fixed a plate 26 upon which is movable a cage 27 having a roll 28 mounted transversely therein. This cage is held against lateral movement by the plate 26 and a spring 29 bears against the underside thereof and exerts its tension so as to move the same upwardly and thereby maintain the periphery of the roll 28 in contact with that of the ring 20. This spring, however, is only of sufficient strength to maintain the weight of the cage and the roll, thus applying practically no friction to the surface of the ring 20 by reason thereof.

It is obvious that when the ring 20 is rotated in the direction of the arrow shown in Figures 1 and 3 that the roll 28 will rotate in the cage 27 without interfering therewith, but instantly grips and holds the ring 20 against movement in the opposite direction. This results from the fact that the horizontal center of the roll 28 is below that of the shaft 16 so that practically the periphery of the ring 20 between the horizontal center of the roll 28 and that of the shaft 16 is an inclined cam or wedge face, which narrows the space within which the roll 28 can move in an upward direction.

Thus the ring 20 can move in a continuous rotary path in one direction without interference by my improved gripping mechanism, but instantly the parts become locked if any attempt is made to reverse the direction of the rotation thereof.

Occasionally it is desirable that the ring 20 may be permitted to rotate in both directions, as when material is being fed by hand, for adjustment of the parts and for other reasons.

To provide means for moving the roll 28 so that it will be held out of engagement with the periphery of the ring 20, I have provided a lever 30 that is pivoted at 31 to the bracket 21, and having an arm 32 that pro-

jects inwardly and over the top of the cage 27.

This lever is connected by the link 33 with the handle 34 pivotally mounted upon the frame 10 by the stud 35. When the handle 34 is moved from the full line position to the dotted line position of Figure 1, the lever 30 is rocked so that the arm 32 thereon engages the top of the cage 27 and moves and holds the same in its down position against the tension of the spring 29, at which time the roll 28 is out of engagement with the ring 20.

The recess 24 in the bracket 21 is closed on both sides after the parts are assembled therein by the plates 36. The details of the mechanism that actuates the ring 20 in the direction of the arrow in Figure 1 are not shown or described herein, but it may be controlled in part by a lever 37 pivoted to the roll frame 15 having arms 38, 39 and 40 forming part thereof, the arm 40 being in turn connected with the handle 34 by the link 41. When this lever is in the position shown by full lines in Figure 1, the gripping mechanism has a make and break connection with the ring 20, so as to impart an intermittent rotary movement thereto, and at the same time the roll 28 is in such position as to prevent the return movement thereof. However, when the handle 34 is moved to the dotted line position in Figure 1, the lever 37 is in the dotted line position shown in the same figure, at which time the gripping mechanism has been so shifted as to destroy the make and break connection with the ring 20 and no motion is imparted to said ring during the movement of the carrier 18 and at the same time and to save motion of the handle 34 the roll 28 is also moved to such a position as to prevent a gripping action thereon.

It is desirable that the peripheral face of the ring 20 should be free from chips, oil, etc., and for this purpose a holder 42 is provided that is secured to the bracket 21 by the bolt 43 or similar means and within which is a wiper 44 of felt or other material which contacts with the said peripheral face and removes therefrom all foreign matter.

What I claim as new and desire to secure by Letters Patent, is:

1. In mechanism of the character described; a rotary member; means for preventing the movement of said member in one direction, comprising a gripping device having an independently mounted roll that contacts with a portion only of an exterior wall of said rotary member, with movably mounted carriage means for said roll whereby the roll may have movement in two directions independently of the rotary member; and yielding means for moving the carriage in one direction.

2. In mechanism of the character de-

130

scribed; a rotary member; means for preventing the movement of said member in one direction, comprising a gripping device, having an independently mounted roll that contacts with a portion only of an exterior wall of said rotary member, with movably mounted carriage means for said roll whereby the roll may have movement in two directions independently of the rotary member; and 10 positive means for moving the carriage in one direction.

3. In mechanism of the character described; a rotary member; means for preventing the movement of said member in one direction, comprising a gripping device having an independently mounted roll that contacts with a portion only of an exterior wall of said rotary member, with a carrier member for mounting said roll whereby it may 20 have movement in two directions independently of the rotary member; and means for moving the roll carrying member positively in one direction and by yielding means in another direction.

25 4. In mechanism of the character described; a rotary member; means for preventing the movement of said member in one direction, comprising a gripping device having an independently mounted roll that contacts with a portion only of an exterior wall of said rotary member, with independently movable carrier means for mounting said roll whereby it may have movement in 30 two directions independently of said rotary member; and manually actuated means for moving the carrier member in one direction.

5. In combination with a rotary member; of means for gripping and holding the same against rotation in one direction and comprising an element having a rounded surface mounted below a horizontal line that extends through the axis of said rotary member; and a member within which said element is rotatably mounted movable in a 45 path at substantially a right angle to said horizontal line.

6. In combination with a rotary member; of a carriage movably mounted in a part independent of said rotary member; in a path substantially parallel with one of the radii of the rotary member an element, having a rounded surface, journaled in the carriage and held in contact with an exterior wall of said rotary member with a yielding pressure applied against the carriage.

7. In combination with a rotary member; of a carriage movably mounted in a part independent of said rotary member; a roll rotatably mounted in said carriage and held 60 in contact with an exterior wall of said rotary member with a yielding pressure.

8. In combination with a rotary member; of a block connected with a fixed part; a carriage slidably mounted upon said block; and a roll rotatably mounted in said car-

riage, the periphery of which is held in contact with an exterior wall of said rotary member.

9. In combination with a rotary member; of a block connected with a fixed part; a carriage slidably mounted upon said block; a roll rotatably mounted in said carriage, the periphery of which is held in contact with an exterior wall of said rotary member; and means for positively moving said carriage so as to hold the periphery of said roll out of contact with said exterior wall.

10. In combination with a rotary member; of a block connected with a fixed part; a carriage slidably mounted upon said block; a roll rotatably mounted in said carriage, the periphery of which is held in contact with an exterior wall of said rotary member; and means for positively moving said carriage so as to hold the periphery of said roll out of contact with said exterior wall, comprising a lever having an arm thereon that engages said carriage.

11. In combination with a rotary member; of a block connected with a fixed part; a carriage slidably mounted upon said block; a roll rotatably mounted in said carriage, the periphery of which is held in contact with an exterior wall of said rotary member; and means for positively moving said carriage so as to hold the periphery of said roll out of contact with said exterior wall, comprising a manually actuated lever and having an arm that engages said carriage.

12. In combination with a rotary member; of a carriage movably mounted in a part independent of said rotary member; a roll rotatably mounted in said carriage and held in contact with an exterior wall of said rotary member with a yielding pressure; and means for preventing endwise movement of said roll within said carriage.

13. In combination with a rotary member; of a block connected with a fixed part; a carriage slidably mounted upon said block; a roll rotatably mounted in said carriage, the periphery of which is held in contact with an exterior wall of said rotary member; means for positively moving said carriage so as to hold the periphery of said roll out of contact with said exterior wall, comprising a manually actuated lever and having an arm that engages said carriage; a handle; and an operative connection between said handle and lever.

14. In mechanism of the character described; a rotary member; and means for preventing the movement of said member in one direction, comprising a gripping device having an independently mounted roll that contacts with a portion only of an exterior wall of said rotary member; and means for cleaning said exterior wall of foreign substance, comprising a pad of felt or the like, held in contact with said exterior wall at a

point adjacent to said gripping device and in such relation thereto that said exterior wall passes said cleaning mechanism just prior to its engagement with said gripping device.

15. In combination with a rotary member; of means for gripping and holding the same against rotation in one direction and comprising an element having a rounded surface; a member with which said element is connected and moved therewith; means for holding said member against lateral movement; and independently actuated means for moving said member in one direction whereby said element is held out of contact with said rotary member and is free to rotate in both directions.

16. In combination with a rotary member; of means for gripping and holding the same against rotation in one direction and comprising an element having a rounded surface; a member with which said element is connected and moved therewith; yielding means for moving the member in one direction and holding said element in frictional engagement with the rotary member; and independently actuated, positive means for moving said member in the opposite direction, whereby said element is held out of contact with said rotary member and the latter is free to rotate in both directions.

17. In combination with a rotary member; of a block connected with a fixed part; a carriage slidably mounted upon said

block; a roll rotatably mounted in said carriage, the periphery of which is held in contact with an exterior wall of said rotary member; and lever means for positively moving said carriage so as to hold the periphery of said roll out of contact with said exterior wall.

18. The combination with a rotary member; of a block connected with a fixed part; a carriage having a recess in one face thereof and into which projects said block, a recess in the opposite face at substantially right angles to the first mentioned recess; and a roll rotatably mounted in said latter recess, the periphery of which is held in contact with an exterior wall of said rotary member.

19. The combination with a rotary member; of a block connected with a fixed part; a carriage having a recess in one face thereof and into which projects said block, and a recess in the opposite face at substantially a right angle to the first mentioned recess; a roll rotatably mounted in said latter recess, the periphery of which is held in contact with an exterior wall of said rotary member; and a spring between said carriage and an adjacent wall exerting its tension against said carriage to move the same in one direction.

In testimony whereof, I have hereunto affixed my signature.

RICHARD LESTER WILCOX.
